(57) **CLAIM**

The ornamental design for a USB charging station, as shown and described.

DESCRIPTION

FIG. 1 is a perspective view of a USB charging station design showing my new design.

FIG. 2 is a front view of a USB charging station.

FIG. 3 is a rear view of a USB charging station.

FIG. 4 is a left side view of a USB charging station.

FIG. 5 is a right side view of a USB charging station.

FIG. 6 is a top view of a USB charging station.

FIG. 7 is a bottom view of a USB charging station; and, FIG. 8 is an enlarged partial view of encircled area '8' in FIG. 2.

The dash-dash broken lines in the drawings illustrate portions of the article that form no part of the claimed design. The dot-dash lines in the drawings illustrate the portions shown enlarged in the drawings and form no part of the claimed design.
